UNITED STATES PATENT OFFICE

EDWARD S. HALSEY, OF WASHINGTON, DISTRICT OF COLUMBIA

THERMOSTATIC-MODULATING STEAM-INLET VALVE OF RADIATORS

Application filed May 1, 1929. Serial No. 359,552.

The invention relates to thermostatic modulating steam inlet valves of radiators, which valves are preferably connected directly to the top end of the radiator.

5 The invention consists in the features and combination and arrangement of parts hereinafter described and particularly pointed out in the claims.

The drawings represent:

10 In Figure 1 a side view of the invention.

Fig. 2 is a face view of an insulating disc with adjacent parts in section, the view being on line 2—2 of Fig. 1.

15 Fig. 3 is a view in section on the line 3—3 of Figs. 1 and 4.

Fig. 4 is a central longitudinal section of the appliance.

20 Fig. 5 is a view of the valve and detached screw handle without the thermostatic element which may be used in place of the thermostatic means whenever it may be desired to convert the arrangement shown in Fig. 4 into a simple hand operated valve.

25 In the drawings the valve body 1 is adapted to be coupled at its end 1a to the steam radiator in usual manner. The steam supply connection is shown at b.

30 The supply of steam to the radiator is controlled by a valve made up of disc 2 having a Jenkins packing disc 3 to engage the valve seat 4 for closing the inlet port 5. This valve is automatically controlled by thermostatic means which includes a container or cell 6 for a material expansible by heat. It may also be controlled by a hand operation of the parts to shut off steam from or supply the steam to the radiator, certain of the parts belonging to the thermostatic control entering into the manual operation.

35 In carrying out my invention I have sought to provide a valve controlling mechanism capable of automatic operation according to room temperature, capable of operation by hand and capable of adjustment for various temperatures, in which the elements will be few, of economical construction, susceptible of ready and quick assembly, and preferably in which elements perform plural functions in respect to automatic, manual and adjustment operations.

The container 6 for the expansible medium or fluid is of a form to act as a handle for the manual operation of the valve when desired.

55 This container is made up in part by a shell 6a of metal and a bellows 7, which is of an external diameter slightly less than the internal diameter of the casing 6a, leaving a space 8 between, which space is in communication with the end space 9. The volatile fluid occupies these spaces. The bellows is attached liquid tight to the casing 6 at the point 7a.

60 An operating rod 11 extends from the steam inlet valve 2 through the hollow screw stem 22 and insulating disc 25 to a point close to the bellows and with its axis coinciding with the axis of the valve and bellows, and at its outer end said rod is connected at 10 to a lever 65 or link 12 which is pivoted at 13 and depends from said pivot.

65 The lower end of this lever is forked at 14 and receives a pin 15 extending between the two levers or links 16 which are pivoted at 16a. The upper ends of the levers 16 have connected therewith a thrust connection or link 16b, the outer end of which rests in a pocket 17 on the inner side of the bellows head. The shell 6 has feet portions or extensions 18 which are attached by screws 18a to a heat insulating disc or shell 25 with an air space at z between it and the edge of the thermostat shell 6.

70 The insulating disc 25 may be of bakelite. It is attached by screws 26 to a flange 24 of the sleeve or stem 22, which has an external coarse screw thread at 23 fitted to a corresponding screw thread on the interior of a bonnet 20, the flange 20a of which is screw threaded onto the valve body 1, and clamps 75 between itself and the valve body, the flange 19 of a bellows 19a to which the steam inlet valve 2 is connected fluid tight.

75 The sleeve 22, guides the center rod 11, it bearing at its end in said sleeve for only a limited distance at 27. For the major portion of its length the center rod 11 has an air space around it as shown at 28.

80 There may be a screw 29 carried in the end of the rod 11 bearing centrally on the valve 85

disc 2 which may be formed with a depression 2a to receive the end of this screw. This screw adjusts the connection between the valve 2 and the bellows organization within casing 6 for length.

- 5 The sleeve 22 in the position of the parts shown in Fig. 4 has its inner end reaching to a point just in rear of the steam inlet valve 2 and serves as a stop to determine the extent 10 of the open position of the valve or to close it entirely by hand. In this closing the valve by hand the shell 6 of the thermostatic element may be used as a handle to turn the sleeve 22. The bakelite disc 25 may also serve either 15 alone or in connection with said shell 6 as the handle for turning the sleeve for adjusting it in relation to the inlet port or to act as a stop for the valve and to alter the degree 20 of opening of the valve.
- 20 The bakelite disc has a series of openings 30 arranged in a circular row, any one of which may be brought into registry with a spring pin 32, the end of which is of a size to enter the opening. The pin 32 is backed by a 25 spring 33 in the socketed member 34 in which the spring pin is slidably mounted.

By means of the handle portion 35 the spring pin can be retracted out of engagement with the bakelite disc which then can be 30 turned to adjust the sleeve for the desired temperature, and then the spring pin by engaging the opening 30 which has been brought into registry therewith will hold the parts in their adjusted position, it being noted that by 35 turning the thermostatic unit together with the sleeve the steam inlet valve may be adjusted relative to its seat.

In this way the device can be set for different temperatures.

40 The space for containing the volatile fluid may be filled through a nipple 36, the port through which is closed by a screw 37. This nipple is within the bellows where it is protected and the lever power multiplying mechanism is within the casing of the thermostatic 45 element, where it is concealed from view and protected. The pivots 13 and 16 of this lever mechanism are mounted in bearings 38 extending from the bakelite disc 25.

50 Fig. 5 illustrates a valve stem and handle, the latter being of any ordinary form. This stem has a screw threaded portion 23a like the screw thread 23 of Fig. 4 so that this handle and stem can be substituted for the 55 sleeve 22 and the thermostatic elements of Fig. 4 and the valve thus can be converted into one controlled solely by hand instead of by a thermostat.

As above pointed out the thermostatic organization has the capacity for hand operation also, but there are advantages in making the valve casing capable of use either with the thermostatic mechanism or with a hand operated valve stem such as shown in Fig. 5. 60

65 When used in the latter way, the valve stem

of Fig. 5 would be used in connection with the valve 2 of Fig. 4 with its bellows so that the same valve body with its steam inlet valve will serve for either use.

The comparatively slender rod 11 of limited 70 capacity provides a heat conductor whose action is dependable and substantially definite.

The object in using this rod of the form 75 shown surrounded by an air gap for practically its entire length, excepting the small bearing contact at its left hand end, is to get a small definite and dependable transfer of heat from the inlet valve to the thermostat, so that regulating devices can be employed with 80 the knowledge that by making certain adjustments certain results will be obtained. In other words, with a rod having more or less bearing contact with the surrounding sleeve, the conduction of heat would be more or less 85 fickle and not of that degree of definiteness which will enable the operator to calculate on obtaining a certain result from a prescribed adjustment.

The stem or rod receives its major heat by 90 radiation and convection rather than by contact.

It will be observed that the bakelite disc 25 has three screws 26 connecting it with the flange 24 and three other screws 18a connecting it with the feet 18 of the shell or casing 6a of the thermostatic element, and that these two sets of screws are in staggered relation, and thus are widely separated so that the transfer of heat from the valve body to the 95 thermostatic shell is reduced to a minimum so far as any transmission between these suspending connections are concerned. The disc of bakelite forms a shield to prevent heat 100 radiated from the valve body from reaching the thermostatic unit as well as to definitely limit the heat being carried from the valve body by conduction to the thermostatic unit.

There is provided a vane or vanes 18b 105 which are adjustably mounted in relation to the flange 24 on the sleeve 22 so as to regulate the transmission of heat from the valve body to the thermostatic cell. These vanes are pivotally mounted on the insulating disc 25 by the screws 18a and they are separated 110 from the hot flange 24 of the valve stem by a narrow air gap. They preferably receive heat from the valve body by radiation and convection instead of by contact, this effect 115 being due to the narrow air gap, and transmit the heat through the screws 18a to the feet 18 and the thermostat. By using this air gap the transference of heat is rendered more definite than if the transfer were made by contact of the vanes with the flange of the valve body. In other words, this air gap renders the transfer of heat less fickle than would be the case were the vane in contact with a part (flange 24) of the valve body. The degree of 120 heat transferred through the vane may be 125

changed by swinging the vane on its screw as a pivot to cause a greater or lesser area of the vane to underlie the flange 24 on the valve body.

5 This principle of rendering the conduction of heat less fickle is present as before stated in connection with the slender center rod 11 which is surrounded by an air gap.

The amount of heat radiated from the thermostatic cell may be regulated by a ring 39 of bakelite or other suitable material which is adjustably mounted by a screw and inclined slot connection 40 to the feet or brackets 18 on the thermostatic casing, so that the ring may 10 be adjusted to cover more or less of the edge portion of the casing 6a of the thermostat so that more or less of this will be exposed for radiation of heat therefrom. The ring may be adjusted entirely off from the edge portion 15 of the casing so as to leave open the air gap z , so that the air may circulate upwardly between the insulating disc 25 and the thermostat casing to dissipate the heat therefrom and also from the motion transmitting members 20 to keep the same at the desired temperature.

Radiation of heat from the valve body is prevented from reaching the thermostat not only by the shield 25, but also by the air gaps 30 x and y .

It will be noticed that by turning the thermostatic unit, as a handle about its axis, the whole valve mechanism can be adjusted to or from its seat, and when the proper adjustment has been arrived at, the spring pin 32 25 will hold the parts in their adjusted position. This spring pin extends with its axis parallel with the axis of the valve mechanism.

It will be noticed that the shell 6a of the 30 thermostat is open at one end, i. e., at the end where it has spaced apart feet 18, which hold the thermostat in spaced apart relation to the heat insulating disc 25, to provide the air gap z , and that the bellows 7 has its open side 45 facing the same way as the open end of the shell.

This construction provides a cavity for receiving the lever mechanism, and enables access to be had to the filling tube or nipple 50 36. This construction presents a large area of the thermostatic cell for exposure to the air, and renders the thermostat sensitive to temperature changes. The cavity B within the bellows is in communication with the air 55 gap z , and the air within this cavity is influenced by the passage of air into or through the said air gap. The heat insulating disc with the heat insulating ring 39 virtually serves as a closure for the open end of the shell of the thermostat and of the bellows 60 when the ring is adjusted to overlap the edge portion of the shell, but when this ring is adjusted to open the air gap, the cell is exposed to a greater amount of convection air of the room acting on the inner wall which defines 65

the cavity B, in addition to the air flowing over the outer surface of the shell 6a.

The spring pin which holds the rotary parts in position to which they may have been adjusted may be locked by any suitable means against casual operation. A wrench 70 operated set screw may be used for this purpose as shown at 32x.

I use ordinary commercial ether in the thermostatic cell which has a boiling point of about 95° Fahrenheit under normal atmospheric pressure. The transfer of heat to the cell by the slender rod 11, or by any other suitable means, elevates the temperature of the cell. There is no available volatile liquid 75 of constant boiling point and of sufficient stability of character between ethyl chloride with a boiling point of about 52½° F. and sulphuric ether boiling at about 95° F. Consequently I have devised the arrangement of parts described above whereby I insulate the cell from the heat radiated from the valve and its casing and I transfer a substantially definite amount of heat from the valve to the cell by way of the slender rod 11 to raise the 80 working temperature to the neighborhood of 90 96° F.

I claim:

1. In combination in a thermostatically controlled valve for radiators, a valve body, a valve therein, a stem adjustable within the valve body in the direction of the axis of the valve for altering the position of the valve, a thermostat comprising a casing, confining an expandible fluid, a member therein to be affected by the expansion of said fluid, a continuous rod between said member and the valve to transmit heat to said member, said rod extending through the said adjustable stem with an air gap between said rod and stem across which heat is radiated to said rod, substantially as described.

2. Apparatus according to claim 1, in which the adjustable stem serves as a guide means for the rod adjacent the valve, said rod having contact at one end with said guide for a limited distance only and being connected with the thermostatic member at its other end, substantially as described.

3. In combination a valve casing, a valve therein, a sleeve screw threaded into the valve casing for altering the position of the valve, a thermostat connected with said sleeve, a continuous rod extending through the sleeve, said rod bearing on the valve at one end and connected with the thermostat at its other end, to transmit heat to the latter, said sleeve being spaced apart from said rod to transmit heat thereto by radiation across the intervening air gap.

4. In combination a valve casing, a valve therein, a thermostatic unit supported from the valve casing, a heat insulating disc forming part of said support, said disc acting to shield the thermostatic unit from heat radi-

ated from said casing, a rod extending continuously between the thermostatic unit and said valve for heat transference, and means for regulating the temperature of the thermostatic unit, substantially as described.

5. In combination a valve casing, a valve therein, a thermostatic member, a heat insulating member between the thermostatic member and the valve casing to shield the 10 said thermostatic member from the heat radiated from the valve casing and regulable means for varying the circulation of the room air at said thermostatic unit to vary the temperature condition at said unit, substantially 15 as described.

6. In combination a valve casing, a valve therein, thermostatic means carried by the casing for controlling said valve, an operating connection between the said means and 20 said valve and adjustable means independent of said connection in heat conductive connection with a part of said thermostatic means, said adjustable means receiving heat from said casing in different degrees according to 25 its adjustment and conducting said received heat to the thermostatic means, substantially as described.

7. Apparatus according to claim 6 in which the adjustable means receives heat 30 from said casing by radiation across an air gap, substantially as described.

8. In combination a valve casing, a valve therein, thermostatic means carried by said casing and controlling the valve, said thermostatic means including a shell, a heat insulating disc between the valve casing and the thermostatic means and spaced apart from the latter to leave on air gap and heat insulating means for exposing more or less of the 40 said shell at said air gap to the room temperature, substantially as described.

9. In combination, a valve casing, a valve therein, thermostatic means carried by the valve casing and controlling the valve, said thermostatic means being separated from the casing by an air gap, and means for regulating the size of said air gap, substantially as described.

10. In combination in direct control valve 50 mechanism for radiators, a valve casing, a valve therein, thermostatic means supported from the casing and arranged coaxially with the valve, an operating connection between the thermostatic means and the valve, a heat insulating disc arranged coaxially with the valve and thermostatic means, and between the said thermostatic means and the valve casing, and through which disc said operating connection extends, a member independent of said operating connection adjustably mounted on said heat insulating disc and receiving heat by radiation from the valve casing, said adjustable member being heat conductively connected with the casing of the 60

thermostatic means, substantially as described.

11. In combination in a direct control valve mechanism for radiators, a casing, a valve therein, thermostatic means for controlling said valve, arranged coaxially therewith and spaced apart from the casing, a heat insulating shield between the thermostatic means and the casing of the valve, and spaced apart from the thermostatic means to leave an air gap between the shield and said thermostatic means, a ring shaped member extending over said air gap with means for adjustably holding said ring shaped member whereby the air gap may be increased or diminished, substantially as described.

12. In combination in apparatus of the class described, a valve casing, a valve therein, a thermostatic means arranged coaxially with the valve and supported from the valve casing, a heat insulating disc between the valve casing and the thermostatic means, a member adjustably mounted on the heat insulating disc and arranged to receive heat from the valve casing, said member being heat conductively connected with the shell of the thermostat across an air gap between the said disc and said shell, and a heat insulating ring adjustable in relation to said air gap and adapted to shield more or less of the shell of the thermostat, substantially as described.

13. In combination in a direct control valve mechanism for radiators, a valve casing, a valve therein, thermostatic means for controlling the said valve, including a shell, an insulating disc between the casing of the valve and the thermostatic shell, said shell having spaced apart feet secured to said insulating disc whereby said thermostatic means is supported in space relation to said disc, means for connecting the said disc with the valve casing, and a ring for enclosing more or less of the air gap between the disc and the shell of the thermostat and for enclosing more or less of the edge portion of said shell, said ring being adjustably mounted, substantially as described.

14. In combination in a direct control valve mechanism for radiators, a valve casing, a valve therein, a thermostat arranged coaxially with the valve and supported from the casing, a heat insulating disc between the valve casing and thermostat, said thermostat comprising a shell having a cavity adjacent but spaced apart from the heat insulating disc and a bellows within the shell having a cavity end facing the same way as the cavity of the shell, said cavities communicating with the air gap between the shell and the insulating disc, a connection between the valve and the bellows, extending into said cavities, and means for regulating the passage of air through the air gap substantially as described.

15. Apparatus according to the preceding claim in which the regulating means varies

the size of the said air gap between the insulating disc and shell, substantially as described.

16. In combination in a direct control valve mechanism for radiators, a thermostat supported from the valve casing coaxially with said valve, a heat insulating disc between the valve casing and the thermostat, from which the thermostat is separated by an air gap, heat conduction connections to the shell of the thermostat, extending across said air gap, means for regulating the conduction of heat through said connections, and means for regulating the passage of air through said air gap and into contact with said connections, substantially as described.

17. In combination in a direct control valve mechanism for radiators, a steam inlet valve or valve casing, a thermostatic cell for controlling said valve, a heat insulator between the thermostatic cell and the valve casing spaced apart from both the cell and said casing, and means for conducting heat from the valve to the interior of the thermostatic cell to raise the temperature thereof to the desired degree above room temperature, said means comprising a rod extending continuously from the valve to the cell through the heat insulator, the said cell being exposed to the room temperature for the dissipation of its heat, substantially as described.

18. In a direct control valve mechanism for radiators according to claim 17, means for regulating the dissipation of heat from said cell, substantially as described.

19. In combination a valve body, a valve therein, a thermostat supported from the valve body, a rod extending continuously from the valve to the thermometer, said valve body having a sleeve therein closely conforming to said rod but with a small air gap surrounding the rod for the major portion of its length, across which air gap the said rod receives heat by radiation from said sleeve, a heat insulator between the valve body and the thermostat and from which the thermostat is supported with an air gap between said insulation and the thermostat, and across which air gap the said rod extends, and means for controlling the passage of air through said air gap substantially as described.

20. In combination a valve casing, a valve therein, thermostatic means carried by the casing for controlling the valve, and adjustable means in heat conducting connection with a part of the said thermostatic means, said adjustable means being adjustable towards and from an adjacent heated part of the apparatus to receive more or less heat therefrom according to its adjustment for transfer to the thermostatic means.

21. In a direct control valve mechanism for radiators, the combination of a valve body, a valve therein, a thermostat supported

by the valve body, a rod extending continuously from the valve to said cell to conduct heat to said cell, said valve body having a wall portion surrounding the said rod with a restricted air space between it and the rod extending the major portion of the rod's length so that the rod will receive a substantially definite amount of heat by radiation from said wall portion substantially as described.

22. Apparatus according to claim 21 in which the said restricted air space has communication with the room atmosphere only at the point where the rod emerges from the valve body.

23. Apparatus according to claim 21 in which means are associated with the cell to regulate the rate of heat dissipation from said cell.

24. Apparatus according to claim 21 in which a heat insulating member is arranged between the valve body and the cell and through which the said rod extends, and means for regulating the rate of heat dissipation from said cell.

25. In combination, a valve casing and valve therein, a thermostat supported from the valve casing, a heat shield between the casing and the thermostat and providing an air gap between the casing and shield, and an air gap between the shield and the thermostat, heat conducting means connected to the thermostat and bridging said last-named gap and extending past said shield and into heat receiving relation to the first-named air gap to receive heat from the casing, whereby heat received from said first-named air gap is transmitted through said means to said thermostat, and valve actuating means operatively connecting said valve to the thermostat.

26. A structure according to claim 25, in which said heat conducting means is regulatable as to the extent to which it may extend into said first-named air gap to thereby regulate the degree of heat transmitted by said means to the thermostat.

27. A structure according to claim 25, in which means is provided to regulate the area of the air gap between the shield and the thermostat.

28. A structure according to claim 25, in which a vane member adjustably mounted in said first-named air gap conducts heat to said heat conducting means.

29. In combination, a valve casing and valve therein, a supporting member receiving heat by conduction from said casing, a heat shield mounted on said member and spaced therefrom to form an air gap between said member and shield on the side toward the casing, a thermostat supported on the opposite side of said shield and spaced therefrom to form an air gap between the shield and thermostat, a heat conducting valve actuati-

ing means operatively connecting the valve to the thermostat, said means extending through said shield and bridging said air gaps, heat conducting means extending from the thermostat past said shield and into the air gap between the shield and said supporting member, means for regulating the amount of heat transmitted by said heat conducting means, and means for regulating the air flow through the air gap between the shield and the thermostat.

In testimony whereof, I affix my signature.
EDWARD S. HALSEY.
